LIFTER MOTION OF SPINNING MACHINES

Edward Kinsella and Charles Wesley Addy, Spondon, near Derby, England, assignors to Celanese Corporation of America, a corporation of Delaware

Application August 20, 1935, Serial No. 36,955
In Great Britain September 17, 1934

10 Claims. (Cl. 242—43.3)

This invention relates to the lifter motion of spinning machines for twisting or doubling yarns, such as ring-spinning, flyer-spinning and cap-spinning machines.

5. In machines of this type the traversing of the yarn being spun upon bobbins or other yarn packages on which it is to be collected is effected by means of a vertically reciprocated lifter rail on which are mounted either the packages on 10 which the yarn is being wound or guide means for conducting the yarn to such packages. The vertical movements of the lifter rail are derived from the movements of a horizontally-reciprocated traverse rod extending the length of the 15 lifter rail. Movement is transmitted from the traverse rod to the lifter rail by means of lifter rods depending from the lifter rail, and lifting chains attached to the bottom ends of the lifter rods, the chains passing over sprockets or flanged 20 wheels disposed at the level of the traverse rod, and being attached to the traverse rod. The traverse rod is reciprocated horizontally by means of a cam-operated lever connected at its upper 25 end to the traverse rod by means of a connecting rod. In order to adjust the length of traverse, the position of the connection between the cam-operated lever and the connecting rod is altered, the pivot of the connecting rod fitting into a slot 30 in the end of the lever, and being adjusted to any desired position along the length of the slot.

This arrangement for the actuation of the traverse rod is liable to certain disadvantages. For example, the obliquity of the connecting rod gives rise to variations in traversing and to consequent uneven layering of the yarn on the packages. Since such obliquity varies in accordance with the adjustments for the length of traverse, it is difficult or impossible to compensate for it by suitable adjustment of the contour of the cam. 40 Furthermore, precision in the adjustment for the length of stroke is difficult. It is an object of the present invention to provide means for actuating the traverse rod of the spinning machine which shall be free from the above disadvantages.

According to the present invention, actuation of the traverse rod of a spinning machine is effected by means of a cam-operated lever rocking about a pivot, the position of which with reference to the machine may be adjusted in the direction of the length of the lever in order to adjust the length of traverse.

While the invention is applicable generally to yarn twisting and doubling machines in which the traverse is derived from the horizontal move-

ments of a traverse rod, it is particularly applicable to machines in which the yarn is collected on flanged bobbins, the precise adjustment of the length of traverse being of especial importance in this case. Thus, the invention is particularly applicable to cap-spinning machines employed in the collection of artificial yarns continuously with their production by the dry or evaporative method.

By way of example a cap-spinning machine provided with actuating means according to the invention will now be described in greater detail with reference to the accompanying drawing, in which

Figure 1 is a front elevation of the machine, 15

Figures 2 and 3 are a side elevation partly in section and a front elevation partly in section respectively of the actuating means on a larger scale than Figure 1, and

Fig. 4 is an enlarged sectional view of a detail 20 of the machine taken on the line 4—4 of Fig. 1.

Referring to Figure 1, the machine comprises a spindle rail 1 on which are mounted a number of stationary spindles 2 secured to the spindle rail by means of collet mountings 3, as described, 25 for example, in our U. S. application S. No. 36,953 filed August 20, 1935 corresponding to British application No. 26635/34 filed 17th September 1934. The spindle rail 1 is made in sections individually mounted upon the frames 4 of the 30 machine. The caps 5 of the machine are mounted at the tops of the spindles 2, the spindles 2 passing through holes in a lifter rail 6 disposed between the spindle rail 1 and the caps 5. Mounted in bearings upon the lifter rail 6 and 35 surrounding the spindles 2 are driving whirls 8 driven in pairs by driving belts 9.

The lifter rail 6 is mounted on the upper end of a number of lifter rods 11 which pass through holes 12 in the spindle rail and is caused to rise 40 and fall by a horizontal motion of traverse rods 13, which are of the kind described in our U. S. application S. No. 36,956 filed Aug. 20, 1935 corresponding to British application No. 26637/34 filed 17th September 1934. The lifter rods 11 are 45 connected to the traverse rods 13 by means of chains 14 secured to the lower ends 15 of the lifter rods 11 and to yokes 16 disposed between the traverse rods 13. Between the yokes 16 and the lower ends 15 of the lifter rods 11, the chains 50 14 pass over sprockets 17 mounted on the frame of the machine. The traverse rods 13 are mounted, as is described in our U. S. application S. No. 36,954, filed August 20, 1935 corresponding to British application No. 26638/34 filed 17th Sep- 55

tember 1934, on quadrants 18 pivoted near the base of the machine at 19, and connected by means of tapes 20 running over the arcuate parts of the quadrants 18, and secured to the 5 traverse rods 13.

The mechanism according to the present invention for actuating the traverse rods 13 is shown at the right-hand side of Figure 1, and in greater detail in Figures 2 and 3. The machine may be divided into two parts, and provided with two of such actuating means, one at each end, such means being preferably disposed to cause one half of the machine to work in opposition to the other. The actuating mechanism is in the form of a unit which may be applied as a whole to an existing cap-spinning machine.

The assembly comprises a frame 21 at the upper end of which are horizontal slides 22 and a cross-head 23 sliding therein, the cross-head being adapted for attachment to the double traverse rod 13. At the lower end of the frame 21 is a bell-crank lever 24, to one arm of which a rocking shoe 25 is pivoted at 26. The other arm 27 of the bell-crank lever is tapped at 28 to take a positioning screw 29, the end of which bears against the frame 21, while a second screw 30, screwing into the frame of the actuating mechanism at 31, bears against the arm 27 of the lever 24, the two screws 29, 30 preventing movement of the bell-crank lever 24 in either direction. To the pivot of the bell-crank lever there is attached an arm or pointer 32 which reads against a scale 33 on the frame 21, the end of the arm 35 being marked with a vernier scale 34 for fine adjustment of the position of the bell-crank lever 24 by means of the positioning screws 29, 30.

The operating lever 35, the lower half of which is of T section is secured at its upper end 36 to the horizontally-sliding cross-head 23, while the flange 40 forming a part of the T section at its lower end fits against and slides in contact with the pivoted shoe 25 provided with flange 41 at 26 on the bell-crank lever 24. In the middle of the lever is a cam bowl 37 which is acted upon by a heart-shaped cam 38 mounted on a shaft 39 in the frame 21 and rotated by any suitable means (not shown). The assembly of the machine is such that the lower end of the lever 35 is maintained in sliding contact with the shoe 25 pivoted at 26 on the bell-crank lever 24 by the force in the traverse rods 13, such force either being derived from the weight of the lifter rail 6 and the parts 7-10 carried thereby or from 55 counter-balance means which compensate for such weight as described, for example, in our U. S. application S. No. 36,952 filed August 20, 1935 corresponding to British application No. 26636/34 filed 17th September 1934.

60 In the operation of the device, the upper end 36 of the lever 35 moves along a horizontal line, being constrained by the slides 22 of the cross-head 23 to which the lever is attached. The tension in the traverse rods 13 in combination 65 with the action of the operating cam 38 holds the lower end of the lever against the rocking shoe 25, and the cam 38, in rotation, forces the upper end 36 of the lever, and the cross-head 23 to which it is attached to perform the desired horizontal movements. The lower end of the lever 35 slides to a small extent during the operation of the machine against the pivoted shoe 25 on the bell-crank lever 24. The freedom of the lever 35 to slide in the pivoted shoe 25 permits 70 the upper end of the lever 36 to be directly con-

nected to the traverse rod and to follow a horizontal linear movement. While this sliding causes a slight variation in the arm of the lever between its lower end and the cam bowl on which the cam acts, this variation may be compensated 5 for by the profile of the cam.

When adjustment of the length of traverse is desired, the position of the bell-crank lever 24 is altered by means of the two set screws 29, 30 acting thereon, the shoe 25 sliding to a different point near the lower end of the actuating lever 35 so as to alter the arm of the lever. Since adjustment is effected by varying the position of the pivot which in the operation of the machine is substantially stationary, and can therefore be 15 made of solid construction, fine adjustment is more easily obtainable. Moreover, by the use of a single lever, the difficulties arising from the obliquity of the connecting rod are overcome. The small variations in the arm of the lever during 20 the operation of the machine remain the same, however, notwithstanding the general alteration in the position of the pivot with respect to the lever, and in consequence the corrections made to the shape of the cam 38 are effective 25 whatever the position of the bell-crank lever 24 and of the lower pivot of the operating lever 35.

What we claim and desire to secure by Letters Patent is:—

1. In a spinning machine comprising a longitudinally moving traverse rod for effecting a traversing motion, means for actuating said traverse rod, comprising a lever directly secured at one end to said traverse rod, a pivot for the other end of said lever, said lever being mounted to 30 slide against said pivot during the traversing motion, cam means for rocking said lever about said pivot, and means for adjusting the position of said pivot in the direction of the length of the lever in order to adjust the length of traverse. 40

2. In a spinning machine comprising a longitudinally moving traverse rod for effecting a traversing motion, means for actuating said traverse rod, comprising a lever, a cross-head at one end of said lever, slides for said cross-head 45 parallel to the motion of said traverse rod, said cross-head being connected to said traverse rod and to one end of said lever, a pivot for said lever at the other end thereof, cam means for rocking said lever about said pivot, and means for adjusting the position of said pivot in the direction of the length of the lever in order to adjust the length of traverse. 50

3. In a spinning machine comprising a longitudinally moving traverse rod for effecting a 55 traversing motion, means for actuating said traverse rod, comprising a lever, a cross-head at one end of said lever, slides for said cross-head parallel to the motion of said traverse rod, said cross-head being connected to said traverse rod and 60 to one end of said lever, a shoe against which the other end of said lever is adapted to slide, a pivot for said shoe, cam means for rocking said lever about said pivot and means for adjusting the position of said pivot in the direction of the length 65 of the lever in order to adjust the length of traverse.

4. In a spinning machine comprising a longitudinally moving traverse rod for effecting a traversing motion, means for actuating said traverse 70 rod, comprising a lever, a bell-crank lever, a pivot for said first lever on one arm of said bell-crank lever, cam means for rocking said lever about said pivot, and means for adjusting the angular position of said bell-crank lever so as to adjust 75

the position of said pivot in the direction of the length of said lever in order to adjust the length of traverse.

5. In a spinning machine comprising a longitudinally moving traverse rod for effecting a traversing motion, means for actuating said traverse rod, comprising a lever, a bell-crank lever, a pivot for said first lever on one arm of said bell-crank lever, cam means for rocking said lever about said pivot, a screw fitting in the other arm of said bell-crank lever and bearing against the frame of the machine, and a second screw fitting into the frame of the machine and bearing against said other arm of the bell-crank lever, 15 said screws being adapted to adjust the angular position of said bell-crank lever so as to adjust the position of said pivot in the direction of the length of said lever in order to adjust the length of traverse.
20. 6. In a spinning machine comprising a longitudinally moving traverse rod for effecting a traversing motion, means for actuating said traverse rod, comprising a lever, a bell-crank lever, a pivot for said first lever on one arm of said bell-crank lever, 25 cam means for rocking said lever about said pivot, a screw fitting in the other arm of said bell-crank lever and bearing against the frame of the machine, a second screw fitting into the frame of the machine and bearing against said other arm of the bell-crank lever, 30 said screws being adapted to adjust the angular position of said bell-crank lever so as to adjust the position of said pivot in the direction of the length of said lever in order to adjust the length 35 of traverse, and a scale in connection with said pivot to facilitate the adjustment of the length of traverse to the desired length.
7. In a spinning machine comprising a longitudinally moving traverse rod for effecting a 40 traversing motion, means for actuating said traverse rod, comprising a lever, a bell-crank lever, a pivot for said first lever on one arm of said bell-crank lever, cam means for rocking said lever about said pivot, means for adjusting the 45 angular position of said bell-crank lever so as to adjust the position of said pivot in the direction of the length of said lever in order to adjust the length of traverse, a scale fitted to the frame of the machine and a scale fitted to said bell- 50 crank lever, said scales constituting vernier means for facilitating the adjustment of the length of traverse to the desired length.

8. In a spinning machine comprising a longitudinally moving traverse rod for effecting a traversing motion, means for actuating said traverse rod, comprising a lever, a cross-head secured to one end of said lever and to said traverse rod, 5 slides for said cross-head parallel to the motion of said traverse rod, a shoe against which the other end of said lever is adapted to slide, a bell-crank lever, a pivot for said shoe on one arm of said bell-crank lever, a screw fitting into the other arm of said bell-crank lever and bearing against the frame of the machine, a second screw fitting into the frame of the machine and bearing against said other arm of the bell-crank lever, 10 said screws constituting means for adjusting the position of said pivot along the length of said first lever so as to adjust the length of traverse, cam means for rocking said lever about said pivot, a scale secured to the frame of the machine and a scale secured to said bell-crank lever, said 15 scales constituting vernier means for facilitating the adjustment of the length of traverse to the desired length.

9. A cap-spinning machine comprising a vertically reciprocating lifter bar, whirs mounted 25 thereon for the reception of bobbins, a longitudinally moving traverse rod for effecting a vertical reciprocating motion of said lifter rail and means for actuating said traverse rod, said means including a lever connected directly at one end 30 to said traverse rod, a pivot for the other end of said lever, said lever being mounted to slide against said pivot during the traversing motion, cam means for rocking said lever about said pivot, and means for adjusting the position of said 35 pivot in the direction of the length of the lever in order to adjust the length of traverse.

10. In a spinning machine comprising a longitudinally moving traverse rod for effecting a traversing motion, means for actuating said traverse rod, comprising a lever directly connected at one end to said traverse rod, a pivot for the other end of said lever, said lever being mounted to slide against said pivot during the traversing motion, a cam for rocking said lever about said 45 pivot, a cam bowl mounted on said lever and adapted to be actuated by the cam, and means for adjusting the position of said pivot in the direction of the length of said lever in order to adjust the length of traverse. 50

EDWARD KINSELLA.

CHARLES WESLEY ADDY.
